A. PARKS

CARPENTER'S PLANE

Filed April 25, 1923

Inventor
Alonzo Parks

John A. Bremhardt.

Attorney

UNITED STATES PATENT OFFICE.

ALONZO PARKS, OF CLEVELAND, OHIO.

CARPENTER'S PLANE.

Application filed April 25, 1923. Serial No. 634,581.

To all whom it may concern:

Be it known that I, ALONZO PARKS, a citizen of the United States, residing at Cleveland, in the county of Cuyahoga and State of Ohio, have invented certain new and useful Improvements in Carpenters' Planes, of which the following is a specification.

This invention relates to carpenters' planes, and has for its object to provide an improved construction by means of which planes of different kinds may be mounted in the same stock or face plate, and bits of different kinds used accordingly suitable to the work at hand. By these means the weight of a number of different planes can be reduced since the stock, which is the heaviest part of a plane, can be used with different bits or throat pieces.

The invention will be understood from the following description and the accompanying drawings in which Fig. 1 is a section of the plane. Fig. 2 is a section of the stock detached. Fig. 3 is the top of Fig. 2. Fig. 4 is a section on the line 4—4 of Fig. 1.

The plane block or stock is indicated at 6, and it may be made of metal if desired. It has a recess 7 at about the middle thereof, to receive the other parts of the bit, this recess having side walls 8 to form a box or cavity and prevent lateral movement. The face plate 9 forms the bottom of the cavity and has a throat 10, in front of which the block is undercut as indicated at 11 to receive a lip 12 on the front of a casing 13 which carries the throat piece 14 and bit 15, clamped to the throat piece in any suitable manner; and the bottom 16 of the casing carries the main handle 17, the front 18 of the casing fitting against the front wall of the recess 7 with the lip 12 in the groove 11. The rear end of the casing is held in place by any suitable latch. I place a spring latch 21 the bolt of which engages in a hole 22 in the rear part of the stock. The side edges of the casing overlap the edges of the walls 8.

By releasing the catch 21, the bit casing can be tilted up until the lip 12 can be withdrawn, and the whole casing can then be removed from the recess 7. Accordingly, a different bit casing can be put in place, and so the same stock or face plate can be used for a variety of bits, it being only necessary to take out one casing and insert another, as the nature of work may require. Or, a stock of different face plates can be made and applied to the same bit casing, permitting a variety of uses without the weight of a considerable number of complete planes.

I claim:

1. A plane comprising a stock having a recess and a throat in the bottom of the recess, and a bit casing fitting in the recess and removable as a unit therefrom and having a lip fitting in the throat, and means to hold the casing in the recess.

2. A plane comprising a stock having a recess and a throat in the bottom of the recess, and a bit casing fitting in the recess and removable as a unit therefrom and having a lip fitting in the front, and means to hold the casing in the recess, the front wall of the recess being undercut at the throat to receive a lip of the casing.

3. A plane comprising a stock having a recess and a throat in the bottom of the recess, and a bit casing fitting in the recess and removable as a unit therefrom and having a lip fitting in the throat, and means to hold the casing in the recess, the front wall of the recess being undercut at the throat to receive a lip of the casing, and a catch engageable between the stock and the casing, at the rear end of the latter, to hold the casing in place.

In testimony whereof, I affix my signature in presence of two witnesses.

ALONZO PARKS.

Witnesses:

JOHN A. BOMMHARDT,
BESSIE F. POLLAK.
